UNITED STATES PATENT OFFICE.

GEORGE MCG. MORRIS, OF CINCINNATI, OHIO.

AUTOGRAPHIC REGISTER.

SPECIFICATION forming part of Letters Patent No. 508,552, dated November 14, 1893.

Application filed January 3, 1893. Serial No. 457,184. (No model.)

To all whom it may concern:

Be it known that I, GEORGE MCG. MORRIS, a citizen of the United States, residing at Cincinnati, Ohio, have invented new and useful Improvements in Autographic Registers, of which the following is a specification.

My invention relates to autographic registers, its object being the production of a cheap and efficient manifolding register adapted to the usual needs and purposes of such devices.

To this end it consists, generally, in a casing adapted to hold the paper-holding, feeding, and cutting-devices, and to serve as a desk or writing tablet—my improvement being concerned in the simplicity and convenience of construction and arrangement of parts with respect to the efficiency of its operation while in use, and also with respect to the convenience of taking out or replacing rolls, &c.

Mechanism embodying my invention is illustrated in the accompanying drawings, in which—

Figure 1, is a perspective elevation of the device complete, indicating in dotted lines the position of the register when opened and thrown back upon its base for putting in a new roll. Fig. 2, is a detail perspective of the front end, showing the propelling roll thrown back to adjust the paper strips with reference to the dividing bar. Fig. 3, is a cross section of the propelling roll, dividing bar, cutters, and paying-out shield in diagrammatic form, showing their functional action upon the paper strips. Fig. 4, is a plan view of the cutting shears detached. Fig. 5, is a detail longitudinal cross-section of the supply roll, showing construction of its pintle and the functional relations of the brake.

Referring now to the drawings: A, designates the general containing casing consisting of a box of rectangular horizontal cross-section, hinged at the rear upon a suitable base, A', and provided in front with a suitable lock, a, securing it to the base, A'. The top of the casing, A, is curved downward at the rear and slopes thence toward the front: and is provided with an exterior rectangular frame, a', hinged at the sides of the casing at its highest portion and extending toward the front—the frame being a guide and protec-

tion, merely, to the paper strips paid over the top of the casing as hereinafter described. The front of the box is open toward the top—the open space being occupied by a roller, the dividing-bar, and fixed cutting-bar, as herein-after described—and the lower part a², of the front is inclined inward as shown to co-operate with the dividing-bar in delivering the strips outwardly and inwardly as herein specified.

The paper strips—one or more—are carried upon a roll, C, (its position being indicated by dotted lines in Fig. 1,) thence upward through a slit in the top of the casing and over an anti-friction roller, b', along the inclined top of the casing beneath the guide frame, a', and downward at the front of the frame over a second anti friction roller, b², there located. Just below the horizontal axial plane, and in front, of the roller, b², is placed a cross-bar, c, arranged tangentially to the roller, b², in a vertical plane: and immediately beneath the cross bar, c, is placed the fixed member, d', of a pair of cutting bars, d', d², (to be described more fully) arranged horizontally with its cutting edge at its under-surface rearward. The dividing bar, c, and the member, d', of the cutting shears, are preferably carried, as shown, upon brackets, z, attached by screws to the casing: so that the entire cutting apparatus may be, with facility and convenience, removed for sharpening the knives, &c. This attachment fixes the relation of these parts to each other; and the attachment of the brackets to the casing at screw holes duly provided, secures the proper relation of all parts to the feed-out rolls and the other co-operating elements. Immediately beneath and slightly rearward of the cutting-edge of the member, d', stands the upper edge of the inclined portion, a², of the casing-front—the relation of the parts being clearly shown in Fig. 3. The paper-strips, drawn from the supply-roll and passing down over the anti-friction roll, b², are divided over the bar, c, one or more (as arranged, as shown at p') passing inward within the casing, A, and the others (p²) being deflected outward by the inclined part, a², of the casing.

The cutting device, shown in detail in Fig. 4, is arranged to operate beneath the anti-friction roll, b², and consists of two shear-members, d', d², pivoted at their correspond-

ing ends at d^3 . One of these members, d' , is fixedly secured to the casing A, in the described relation to the dividing bar, c , and the other member, d^2 , swings in a guide slot, 5 s, of the casing beneath and rearward of the member, d' , and is operated against the force of a retaining spring, O, by means of a projection d^4 , formed to be conveniently engaged by the hand.

10 To feed the paper-strips forward, I provide a friction propelling roller e, journaled in a housing, E, pivotally connected to the casing A, at opposite sides, below and in front of the cutting shears, by side arms, e' , so as to 15 swing outward as indicated in Fig. 2. The housing frame is provided with spring-extensions, e^2 , of its side arms, which are engaged over studs or projections, e^3 , at opposite sides of the casing, and serve to hold the friction 20 roller e, against the anti-friction roller, b^2 , by a self-adjusting tension. One of the journals (on the right hand as herein shown) of the roller, e, is projected through the side of the housing, E, and carries a crank, f, by which 25 it is turned; and thus the paper-strips are fed forward. An adjustable plate, g, is provided, secured to the casing, A, below the slot, s, by screws, g' , passing through upwardly elongated holes of the plate, whereby 30 the plane of travel of the movable shear-member, d^2 , is adjusted to bring the cutting edges of the shears in proper relation, and take up any lost motion due to wear.

The supply roll, C, consists of one or more 35 strips of paper wound upon a perforated mandrel, h, preferably of wood, carried upon a pintle, i, circumferentially grooved at one projecting end (Fig. 5) and provided with a button, h' , at the other end. Adjacent to the button, h , are one or more radial lugs, h^2 , which engage and rotate the mandrel, h, as required. 40 The groove in the projecting end opposite the button, receives a spring-wire, y, secured to the outside of the casing, A, and bearing radially against the pintle, i, in its groove thereby holding the pintle against longitudinal displacement and at the same time operating as 45 a friction-brake to prevent overrunning of the roll.

50 The register is used in the usual manner to record a sale or other transaction in "manifold." I have not herein shown the carbon sheets, as they are common in these and similar devices, being attached across the tablet. 55 top of the casing between the strips of paper. The record being made upon the upper strip within the guide frame, a' , and by pressure of the pencil recorded in manifold upon the under strip or strips, the crank, f, is rotated 60 and the paper drawn forward sufficiently, when the cutting bar, d^2 , is drawn forward in its slot, severing the strips at the cutting edges of the bars, d', d^2 , as the meeting-point of the edges shift across the strip. The severed ends of the inside strip or strips—as the strips are divided by the dividing bar, c ,—drop down within the casing out of reach of

the attendant, while the outer strips, are deflected forward and outward by the inclined shield, a^2 .

70 When necessary to remove the accumulated inner memoranda, the front of the casing is unlocked at, a, and the entire casing tilted back upon its base, B, as indicated by the dotted lines in Fig. 1. In this position, also, a new supply-roll may be conveniently substituted. The guide frame, a' , being hinged at its rear to the sides of the casing, is lifted up for convenience in bringing the ends of the new strips through the top of the casing and 75 between the carbon sheets; and, the casing being again let down on its base, the spring-arms, e^2 , are detached from their studs, e^3 , and the housing, E, is tilted forward, as shown in Fig. 2, for convenience in inserting the ends 80 of the strips in proper relation to the dividing bar, c , and shield, a^2 . This done, and the casing locked in its closed position, the apparatus is ready for use.

I prefer to employ paper-strips wound together upon a single supply roll—the curves of their outward path in the apparatus being all such as to make the feed-out uniform: but this is not essential, as separate supply-rolls 85 may be employed; suitably placed and journaled in the casing in the same manner as that described—all feeding outward over the anti-friction rolls, b', b^2 .

90 It will be observed as a material advantage of the apparatus that the casing is substantially closed to any access whatever except by unlocking at its lock, a, and tilting it back upon its base: further, that the casing is entire as a partially closed box, open only at the bottom; and may, if desired, be cast as a 95 single piece: further that its simplicity and compactness render it economical to construct, operate and maintain; and also that the constructive arrangement of parts renders it quite easy to substitute new paper-rolls, to remove the stored memoranda, or to remove the cutting knives for sharpening.

100 The anti-friction rolls b', b^2 , may be fixed surfaces suitably smoothed: but I prefer the use of rollers of wood turned to true cylinders.

105 I claim as my invention, and desire to secure by Letters Patent of the United States, the following:

110 1. An autographic register, embodying a substantially integral casing entirely open at the bottom, containing a paper dispensing roll at the rear, a writing tablet at the top, feed-out rolls at the front of said tablet, cutting mechanism below said feed-out rolls, and a free space for storage of slips beneath said 115 tablet, in combination with a base constituting a bottom for said casing upon which the casing is hinged at the rear and locked in front, whereby upon being unlocked and thrown back upon its hinges the interior of 120 the casing with its contained mechanism is exposed in front of the operator and is lifted away from the stored slips upon the bottom, 125 substantially as set forth.

2. In an autographic register, the combination with an anti-friction roll journaled in the casing at the feed-out end, a roll-housing carried upon radial side-arms and pivoted to the casing to swing toward and from the anti-friction roll, a propelling roll carried in said housing, and a spring arm or arms bearing upon said housing to keep the rolls normally in contact, substantially as set forth.
3. In an autographic register, in combination with an anti-friction roll at the feed-out end of the casing, a roll-housing having radial side arms pivotally supporting the same upon the casing to swing toward and away from the anti-friction roll, a propelling roll journaled in the housing, and spring-extensions of the radial side-arms detachably engaged behind studs or projections of the casing, and, when so engaged, holding the rolls in pressure-contact; and when disengaged, permitting the housing to swing back and out of the way, substantially as set forth.
4. In an autographic register, the combination of a casing containing a paper-dispensing roll at the rear and presenting its top forward of the same as a writing tablet, a pair of feed-out rolls at the front of said tablet, a free open storage space beneath said tablet, a dividing bar beneath said feed-out rolls, and a shearing apparatus arranged and operating horizontally beneath said dividing bar, substantially as set forth.
5. In an autographic register, the combination of a casing containing a paper-dispensing roll at the rear and presenting its top forward of the same as a writing tablet, feed-out rolls arranged in horizontal relations at the front of said tablet; a dividing bar beneath said feed-rolls; a storage receptacle for severed slips beneath said tablet in rear of the dividing bar; a horizontal fixed shear arranged beneath and forward of the dividing bar; and a pivoted movable shear arranged in the rear of said fixed shear to operate therewith across the line of paper feed by a forward movement, substantially as set forth.
6. In an autographic register, the combination of a casing containing a paper-dispensing roll and presenting its top as a writing tablet, a pair of feed-out rolls in horizontal relations at the front of said tablet and casing, a dividing bar beneath said rolls, a pair of cutting shears arranged and co-operating horizontally beneath said dividing bar, an open storage space in the casing beneath said tablet, and a shield constituting the front of the casing below said cutting apparatus, to deflect the outer severed strip outwardly and forward of the casing, substantially as set forth.
7. In an autographic register, the combination of the casing presenting its top as a writing tablet and having an open storage space beneath the same, the horizontally arranged feed-out rolls, the fixed cutting shear below the same, the movable shear pivoted to co-operate therewith in a horizontal forward movement, and a retractile spring attached directly to the pivoted shear and to the casing behind the same to hold the pivoted shear normally open, substantially as set forth.
8. In an autographic register, the combination of a pair of horizontally arranged feed-out rolls at the front of the casing, a dividing bar below and between the same, a fixed cutting bar arranged horizontally below the dividing bar and in front of the line of feed, a movable cutting bar or shear pivoted behind the line of feed to swing across and in co-operation with the fixed cutting bar, and a guide-slot in the side of the casing through which the free end of the movable cutting bar is projected as a handle, and by which it is held and guided in proper plane of movement, substantially as set forth.
9. In an autographic register, the combination of the sides of the casing through which the journals of the dispensing roll are projected, a grooved projection of the journal beyond the casing and a tension spring attached to the casing and bearing radially in the groove, acting both as a brake and retainer to hold the journal in place longitudinally, substantially as set forth.
10. In an autographic register embodying a casing, feed-out rolls, dividing bar, and cutting apparatus, the combination of the feed-out rolls, dividing bar, and the fixed member of the cutting apparatus, with two end-brackets to which the cutting bar and dividing bar are fixedly secured, adapted to be detachably secured as a whole by means of the end-brackets to the casing in position for operation in fixed relations to the co-operating parts, substantially as set forth.

In testimony whereof I have hereunto set my hand in the presence of two subscribing witnesses.

GEORGE McG. MORRIS.
